UNITED STATES PATENT OFFICE.

WILLIAM B. SANDFORD, OF KEWANEE, ILLINOIS.

PIPE-TONGS.

SPECIFICATION forming part of Letters Patent No. 537,487, dated April 16, 1895.

Application filed November 22, 1894, Serial No. 529,677. (No model.)

To all whom it may concern:

Be it known that I, WILLIAM B. SANDFORD, a citizen of the United States, residing at Kewanee, Henry county, Illinois, have invented 5 certain new and useful Improvements in Pipe-Drawing Tools, of which the following is a specification, reference being had to the accompanying drawings, in which—

Figure 1 is a side elevation. Fig. 2 is an 10 enlarged side elevation, part being broken away. Fig. 3 is a plan view, part being broken away. Fig. 4 is a cross section on line 4—4 of Fig. 2.

My invention relates to tools for drawing 15 pipe in the manufacture of butt-weld pipe by drawing a skelp through a bell, and has for its object to provide certain improvements in the tongs described and claimed in a certain application, Serial No. 529,671, of even date 20 herewith, filed by Alfred M. Hewlett, of Kewanee, Illinois. I accomplish this object as hereinafter specified and as illustrated in the drawings.

That which I regard as new will be set forth 25 in the claims.

In the drawings, 5 indicates a stationary jaw. 6 indicates a movable jaw pivoted to said stationary jaw by a pivot 7, as shown in Fig. 2.

30 8 indicates a stationary handle which is fixedly connected to the stationary jaw 5. 9 indicates a rod which is movable longitudinally of said stationary handle and carries at its forward end a plate 10 having an inclined slot 35 11, as shown in Fig. 2.

19 indicates a support for the rod 9, which prevents the rod from moving sidewise when it is reciprocated, as will be hereinafter described.

40 12 indicates a pin carried by the movable jaw 6 near its rear end, which pin projects into the slot 11, as shown in Fig. 4.

By moving the rod 9 and plate 10 forward, the jaw 6 may be moved away from the jaw 5, 45 and vice versa. The rod 9 is connected at its rear end by a pivot 13 to a lever 14 which is pivoted by a pivot 15 to the handle 8, the pivot 15 being forward of the lever 14, as shown in Fig. 2. As indicated by dotted lines in Fig. 50 3, the lever 14 is provided with a slot 16 to receive the pivot 15, so that a slight longitudinal movement of the lever is permitted.

By this construction, when the lever 14 is

thrown forward, as indicated by dotted lines in Fig. 2, the jaws 5—6 may be opened by 55 moving the movable jaw and the jaws may be closed by moving said lever in the opposite direction. It will be seen that when anything is gripped between the jaws, inasmuch as the pin 12 will not lie in the upper end of 60 the slot 11, the pull upon the lever 14 will serve to tighten the grip of the jaws.

That which I claim as my invention, and desire to secure by Letters Patent, is—

1. In a pipe tongs, the combination with a 65 fixed jaw and a movable jaw pivoted thereto, of a handle connected to said fixed jaw, a plate movable longitudinally of said handle, said plate having an inclined slot 11, and a pin carried by said movable jaw and projecting 70 into said slot, substantially as described.

2. In a pipe tongs, the combination with a 75 fixed jaw and a movable jaw pivoted thereto, of a handle connected to said fixed jaw, a plate movable longitudinally of said handle, said plate having an inclined slot 11, a pin carried by said movable jaw and projecting into said slot, and a lever connected to said plate for moving it longitudinally, substantially as described.

3. In a pipe tongs, the combination with a 80 fixed jaw and a movable jaw pivoted thereto, of a handle connected to said fixed jaw, a plate movable longitudinally of said handle, said plate having an inclined slot 11, a pin carried 85 by said movable jaw and projecting into said slot, and a lever pivoted to said handle and connected to said plate, said lever being adapted to be turned to a position parallel with the handle and being movable longitudinally of said handle, substantially as described.

4. In a pipe tongs, the combination with a 90 fixed jaw and a movable jaw pivoted thereto, of a handle connected to said fixed jaw, a plate 95 movable longitudinally of said handle, said plate having an inclined slot 11, a pin carried by said movable jaw and projecting into said slot, a rod 9 connected to said plate, and a support for said rod, substantially as described.

WILLIAM B. SANDFORD.
